COMBINED FIREPLACE BACK AND WATER HEATER STRUCTURE

Charles Walter Perry, Dothan, Ala.

Application June 5, 1934, Serial No. 729,145

4 Claims. (Cl. 126—132)

This invention relates to a combined fireplace back and water heater structure and has for its object to provide, in a manner as hereinafter set forth, a structure of the class referred to for not only constituting an attractive permanent fire resisting back for a fireplace but also providing a water heater.

A further object of the invention is to provide, in a manner as hereinafter set forth, a structure for the purpose referred to which is simple in its construction and arrangement, strong, durable, compact, readily installed with respect to a fireplace, thoroughly efficient in its use, having an artistic front, and comparatively inexpensive to manufacture.

To the above ends essentially, and to others which may hereinafter appear, the invention consists of such parts and such combination of parts which fall within the scope of the invention as claimed.

In the drawing:—

Figure 1 is an elevation of a fireplace and a water supply showing the adaptation therewith of a combined fireplace back and water heater structure in accordance with this invention.

Figure 2 is a side elevation of the structure showing the installation thereof with respect to a fireplace.

Figure 3 is a section on line 3—3 of Figure 2.

Figure 4 is a vertical sectional view of the structure.

A combined fireplace back and water heater structure in accordance with this invention is formed of a single hollow casting 5 constructed from any suitable metallic material.

The casting 5 includes a pair of side walls 6, 7, a top wall 8, a bottom wall 9, a front wall 10 and a rear wall 11. Each side wall is of like form and includes a lower portion 12 of uniform width and an upper portion 13 which is extended forwardly with respect to the portion 12. The contour of the portion 13 is substantially of inverted semi-pear shape. The bottom wall 9 is flat and of a width corresponding to that of the lower portions of the side walls 6, 7. The front wall 10 is formed of a lower vertically disposed straight stretch 14 and an upper curved stretch 15 which is extended forwardly with respect to stretch 14 and is substantially of semi-inverted pear shape. The rear wall 11 is straight throughout. The front wall is integral with the top, bottom and side walls. The side walls are integral with the top, bottom, front and rear walls. The manner of set up to walls 6, 7, 8, 9, 10 and 11 as referred to provides a water chamber 16 formed of an upper portion 17

and a lower portion 18, the former being of materially greater volume than the latter.

Arranged within chamber 16 and integral with the inner face of the top wall 8 and the major portion of the length of the inner faces of the front and rear walls is a pair of spaced parallel vertically disposed webs or reinforcing members 19 which are spaced from the side walls 6, 7. The lower ends of each member 19 is spaced from the bottom wall 9. The members 19 are of like form and each consists of a wide upper part 20 and a narrow lower part 21. The part 20 at its upper and lower ends are provided with openings 22, 23 respectively. The opening 22 is of greater diameter than and extends forwardly with respect to opening 23. The part 21 intermediate its ends is formed with an opening 24 of less diameter than the opening 23. The member 19 in connection with the top, side, front and rear walls of the casting form the chamber 16 into a series of open bottom compartments 25 discharging into the portion 18 of chamber 16. The openings 22, 23 and 24 provide for the passage of the water into and out of the compartments 25.

The outer face of the front wall 10 is formed with a series of spaced upstanding ribs 26 which extend from the top wall 8 to the upper end and spaced from the lower end of the stretch 14 of wall 10. The ribs 26 reinforce and enhance the appearance of said front wall 10. The upper and lower end edges of the ribs 26 are indicated at 27, 28 respectively. The upper end edges 27 of the ribs are vertically disposed and flush with the front of and extend at right angles to the top wall 7. The lower end edges of the ribs 26 extend upwardly at an inclination from the front wall 10.

Each side wall is provided on its outer face with a vertically disposed laterally extending flange 29 corresponding in length to that of such wall. The flange 29 has a portion thereof, indicated at 30 flush with the front edge of the lower portion 12 of the side wall. The remaining portion of the flange 29 indicated at 31 is spaced from the forward and rear edges of the upper portion 15 of the side wall. The purpose of the flanges 29 will be presently referred to.

The side wall 6 at its upper end is formed with an opening 32 for connecting to casting 5 one end of a hot water conducting line 33 which leads from portion 17 of chamber 16 to a water storage tank 34. The side wall 6 is provided in its lower part 16 adjacent the lower end of the latter with an opening 35 for connecting to casting 5 one end of a water feed line 36 which leads from the tank 55

16 to the portion 18 of chamber 16. The side wall 6 is formed in its lower part 16 below opening 35 with an opening 37 for connecting to casting 5 one end of a combined valve controlled drain and water supply pipe 38.

5 A fireplace is indicated at 39 and it includes a top wall 40, a pair of side walls 41, and a support 42. The top wall 40 has a depending part 43 aligning with support 42. The part 43 provides a shoulder 44. Positioned upon support 42 is what 10 may be termed a wedging or positioning strip 45 for casting 5.

When the structure, in accordance with the invention is positioned to provide the fireplace back, the casting is seated upon strip 45; the ribs 26 of the front wall 10 arranged between the side walls 41; the upper end edges 27 of the ribs 26 abutting the shoulder 44, the flanges 29 bearing against the rear of the side walls 41; and that 15 portion of the casting 5 rear of the flanges 29 being extended in a direction rearwardly from the fireplace. The stretch 15 of the front wall 10 and the upper portions 13 of the side walls 6, 7 of the casting will project into the fireplace 39 over and above the grate 45. The lower portions 12 of the 20 side walls 6, 7, the lower stretch of front wall 10 and the lower portion of rear wall 11 will extend below the grate 45. The lower ends 28 of the ribs 26 when the casting 5 is in position, will be arranged in close proximity to grate 45.

30 The casting 5 will be continuously filled with water which will materially increase the durability thereof.

Any suitable connections may be attached to the tank for utilizing hot water therefrom.

35 What I claim is:

1. A fireplace back comprising a vertically disposed hollow casting forming a water chamber; the upper portion of said chamber being of greater 40 volume than its lower portion, the upper portion 45 of the front of said casting being projected forwardly with respect to the lower portion of its front, and said casting being formed therein with upstanding spaced apertured webs extending from a point removed from the lower end thereof to its upper end, said webs being integral with the inner faces of the front, rear and top of the casting.

50 2. A fireplace back comprising a vertically disposed hollow casting forming a water chamber, the upper portion of said chamber being of greater volume than its lower portion, the upper portion 55 of the front of said casting being projected forwardly with respect to the lower portion of its front, said casting being formed on its front with spaced ribs extending from a point removed from its lower end to its upper end, and said casting being formed therein with upstanding spaced webs extending from a point removed from the lower end thereof to its upper end, said webs being integral with the inner face of the front, rear

and top of the casting and each formed with an upper, an intermediate and a lower opening arranged in superposed spaced relation, the diameter of the upper opening being greater than that of the other openings and the diameter of the 5 intermediate opening being greater than that of the lower opening.

3. A fireplace back comprising a vertically disposed hollow casting of substantially inverted semi-pear-shaped contour forming a water chamber, the upper portion of said chamber being of greater volume than its lower portion, the upper portion of the front of said casting being projected forwardly with respect to the lower portion of its front, said casting being formed therein with upstanding spaced parallel webs extending from a point removed from the lower end thereof to its upper end, said webs being integral with the inner faces of the front, rear and top of the casting and each formed with an upper, an intermediate and a lower opening, and said casting having each side thereof formed with a vertically disposed laterally projecting flange extending from the bottom to the top thereof, said flanges having their lower portions aligning with the lower part 25 and their upper portions spaced rearwardly of the upper part of the front of the casting.

4. A fireplace back comprising a vertically disposed hollow casting forming a water chamber, the upper portion of said chamber being of greater 30 volume than its lower portion, the upper portion of the front of said casting being projected forwardly with respect to the lower portion of its front, said casting being formed therein with upstanding spaced webs extending from a point removed from the bottom of said chamber to the top of the latter, said webs being integral with the inner faces of the top, front, sides and rear of the casting and each formed with an upper, an intermediate and a lower opening, said casting being 35 formed on its front with spaced ribs extending from a point removed from its lower end to its upper end, said ribs having their upper end edges disposed vertically and at right angles to the top face of said casting, said casting having one side 40 thereof formed with a pair of superposed spaced openings for connecting therewith water circulating means for said chamber, the lower of said openings being arranged below said webs, said casting having one side thereof provided with an 45 opening below the lower end of said other openings for connecting therewith a combined drainage and water supply line, and said casting having each side thereof formed with a vertically disposed laterally projecting flange extending from the bottom to the top thereof, said flanges having their lower portions aligning with the lower part and their upper portions spaced rearwardly of the upper part of the front of the casting.

60 CHARLES WALTER PERRY.
